Albert W. Brown
ATTORNEY.

UNITED STATES PATENT OFFICE.

CHARLES W. SMITH, OF HAVERHILL, MASSACHUSETTS.

TROLLEY.

No. 921,474

Specification of Letters Patent.

Patented May 11, 1909.

Application filed April 9, 1908. Serial No. 426,158.

To all whom it may concern:

Be it known that I, CHARLES W. SMITH, a citizen of the United States, residing at the city of Haverhill, in the county of Essex and State of Massachusetts, have invented new and useful Improvements in Trolleys, of which the following is a specification.

This invention relates, particularly, to pole-trolleys of electric railways and it consists in 10 the combination with the head of the trolley-pole and the trolley-wheel or sheave of a bearing-block for each journal of said wheel, both of which are detachably held on said head and each of which has an oil-chamber 15 or reservoir with provision for opening and closing it and with a passage leading from it to the wheel-journal and its bearing in the block for the purpose of securing lubrication of said journals and bearings, all substantially as hereinafter described.

The invention is illustrated in the accompanying drawings forming part of this specification.

Figure 1 is an elevation at one side of the 25 pole, in part; the pole-head and wheel. Fig. 2 is a plan view of one half of the wheel and the pole-head and of a bearing-block and a horizontal section of the other half thereof, dotted line 2—2, Fig. 1. Fig. 3 is a vertical 30 edge view of a bearing-block and a similar view of the wheel, in part, and of the portion of the pole-head holding said block. Fig. 4 is a vertical edge view of the pole-head and the upper adjacent part of the pole. Fig. 5 is a vertical edge of a bearing-block detached 35 and in detail. Fig. 6 is a vertical section of a bearing-block detached and in detail, dotted line 6—6, Fig. 1.

In the drawings, A is the upper portion of 40 a trolley-pole having a head B in upward extension thereof.

C is the grooved trolley-wheel or sheave, having, on its opposite sides, similar axial journals D, D.

45 E, E are the opposite bearing-blocks for the wheel-journals D, D.

The upward extending portion of the pole-head B is of fork shape, Fig. 4, and its opposite and parallel tines or sides F are of a corresponding fork-shape and the inner edges G of its tines H are in parallel vertical planes at right angles to the inner and outer faces J, K of the tines or sides F. Each bearing-

block E has a similar groove L along its outer parallel and opposite upright edges M 55 and these several grooves L are of suitable width and depth for the blocks to be entered between the inner edges G of the tines H and so entered to fit said edges and to overlap the portions of the inner and outer faces J, K 60 of the tines F, which are adjacent thereto, Fig. 2. Again each bearing-block at its lower edge has parallel downward projecting ear-pieces N to embrace the sides F of the pole-head B at the inner and outer faces J, K 65 thereof, when the blocks are on the pole-head B as has been explained and thus by means of pins, bolts or other such like fastenings as at O entered therethrough the blocks can and will be secured in position against accidental 70 displacement, while they are free to be detached at pleasure.

P is a horizontal socket in each bearing-block, leading from the inner face thereof, and in each instance of suitable size and 75 depth to receive and make a bearing for a journal D of the trolley-wheel and to permit it to freely turn therein.

Q is a chamber or reservoir for oil or other lubricant in each bearing-block and R is a 80 passage leading from said reservoir to the bearing of the block for the wheel journal and so thereby to secure oiling or lubrication thereof in the running of the trolley-wheel.

S is a screw-stopper or plug for each oil- 85 reservoir Q and on removing which the reservoir is opened to be filled and on replacing it the reservoir is closed.

T is a bushing of the bearing P and wheel-journal D, and, U is a washer on a wheel-journal D between its outside face and the 90 face of the bearing-block toward the wheel.

Having thus described my invention what I claim and desire to secure by Letters Patent is,

The combination with a trolley-pole of a forked upper end-portion or head each tine of which, at its upper end-portion, is of corresponding fork-shape, bearing-blocks in each of said forked-tines, provided, at their opposite side-faces, with flanges overlapping the outer and inner side faces of said tines and with journal-bearings and with downward extensions overlapping said side-faces of said tines, transverse pins or bolts entered through 100 said downward extensions and said tines,

an oil-reservoir in each of said blocks located at one side of its journal-bearing, an inclined oil-passage leading upward from the lower portion of each of said oil-reservoirs to said journal-bearings of the blocks, and a trolley-wheel disposed between and journaled in said block-bearings, all as described, for the purpose specified.

In witness whereof, I have hereunto set my hand in the presence of two subscribing witnesses.

CHARLES W. SMITH.
